By his Attorneys,

Walter L. Martin, Inventor.

C. A. Snow & Co.

UNITED STATES PATENT OFFICE.

WALTER LOWRIE MARTIN, OF MOFFATT'S CREEK, VIRGINIA.

CLOTHES-PIN.

SPECIFICATION forming part of Letters Patent No. 639,259, dated December 19, 1899.

Application filed July 2, 1898. Serial No. 685,076. (No model.)

To all whom it may concern:

Be it known that I, WALTER LOWRIE MARTIN, a citizen of the United States, residing at Moffatt's Creek, in the county of Augusta and State of Virginia, have invented a new and useful Clothes-Pin, of which the following is a specification.

The invention relates to improvements in clothes-pins.

10 The object of the present invention is to improve the construction of clothes-pins and to provide a simple, inexpensive, and efficient one designed to be substantially permanently mounted on a line to prevent it from becoming lost and capable of ready adjustment along a clothes-line to position it properly with relation to the fabric to be clamped and adapted to engage the same both above and below the line to prevent a garment from slipping along the latter.

15 The invention consists in the construction and novel combination and arrangement of parts hereinafter fully described, illustrated in the accompanying drawings, and pointed out in the claims hereto appended.

20 In the drawings, Figure 1 is a perspective view of a clothes-pin constructed in accordance with this invention, the pin being open. Fig. 2 is an elevation of the same, the pin being closed. Fig. 3 is a similar view showing the clothes-pin arranged on a line and illustrating the arrangement of the clamping-coils relative to the same.

25 Like numerals of reference designate corresponding parts in all the figures of the drawings.

1 A designates a substantially U-shaped clothes-pin constructed of a single piece of resilient wire or similar material and composed of sides 2 and 3, connected at the bottom of the pin by a spring-coil 5, and the side 3 is provided at the top of the pin with a transverse portion or arm 4, terminating in a hook 6, which is adapted to engage the side 2, whereby the clothes-pin is locked in its engaging position. The sides 2 and 3 are provided at the center of the clothes-pin with engaging coils 7, arranged in pairs and adapted to clamp a garment or other fabric on a line by engaging the same at the top and bottom of the latter, as clearly illustrated in

Fig. 3 of the accompanying drawings, whereby the garment is effectually prevented from slipping along the line. The coils 7, which are located at opposite sides of the clothes-line 8, are spaced apart sufficiently to engage a garment at the top and bottom of the line, and the said garment is clamped at both sides of the line, as well as at the top and bottom.

55 In order to prevent the clothes-pin from becoming accidentally lost, it is provided at one side adjacent to the coils 7 with a centrally-arranged vertical eye 9, arranged at right angles to the horizontal clamping-eyes 7 and preferably formed by coiling the side 3, as 60 clearly illustrated in the accompanying drawings. The vertical eye 9 may consist of either a single or a double coil, and it permits the clothes-pin to slide along the line to bring it in proper position and is capable of preventing a 65 clothes-pin from becoming accidentally lost.

70 The invention has the following advantages: The clothes-pin, which is constructed of a single piece of wire, possesses great strength and durability and is not liable to 75 break and cannot become lost. It is adapted to be adjusted along a clothes-line and is capable of clamping a garment both above and below the line and at opposite sides thereof and of preventing the said garment from sliding 80 along the latter.

Changes in the form, proportion, and minor details of construction may be resorted to without departing from the spirit or sacrificing any of the advantages of this invention. 85

What I claim is—

1. A substantially U-shaped clothes-pin, the side portions of which are provided at intermediate points with oppositely-located co-operating clamping-coils, one of the arms 90 having an eye located adjacent to one of the engaging coils and designed to receive the clothes-line, combined with means at the extremities of the arms for holding the latter together, whereby the engagement of the coils 95 with each other and the clothes-line is maintained, substantially as described.

2. A substantially U-shaped clothes-pin, both sides of which are provided at points intermediate their ends with oppositely-located 100 co-operating clamping-coils serving to engage a clothes-line on opposite sides, combined

with means at the extremities of the sides for holding the sides toward each other and maintaining the engagement of the coils with each other and the line, substantially as described.

5 3. A clothes-pin comprising two sides provided with clamping-coils arranged in pairs, an eye located at one side of the pin adjacent to the clamping-coils, and an arm arranged at one end of the clothes-pin, connected with 10 one side thereof and provided with a hook de-

tachably engaging the other side, substantially as described.

In testimony that I claim the foregoing as my own I have hereto affixed my signature in the presence of two witnesses.

WALTER LOWRIE MARTIN.
